CASING FOR BEVERAGE DISPENSER

Harry Cormano, Scarborough, N. Y., assignor to Apco,
Inc., New York, N. Y., a corporation of New York

Application February 27, 1956, Serial No. 40,326

Term of patent 14 years

(Cl. D52—3)

The single figure of the drawing is a front perspective view of a casing for beverage dispenser, showing my new design.

The undisclosed side of the beverage dispenser is substantially the same in appearance as the side shown in the drawing.

The dominant features of the design are shown in full lines.

I claim:

The ornamental design for a casing for beverage dispenser, as shown and described.
